UNITED STATES PATENT OFFICE.

PERCY BROWN AND FRANCIS JOHN BOSTOCK, OF HUDDERSFIELD, ENGLAND.

WORM-WHEEL GENERATOR OR MILLING-MACHINE.

1,122,068.

Specification of Letters Patent. Patented Dec. 22, 1914.

Application filed October 8, 1913. Serial No. 794,044.

To all whom it may concern:

Be it known that we, PERCY BROWN and FRANCIS JOHN BOSTOCK, subjects of King George V of Great Britain, residing at Huddersfield, in the county of York, England, have invented certain new and useful Improvements in Worm-Wheel Generators or Milling-Machines, of which the following is a specification.

10 This invention has reference to worm wheel generating or like milling machines, and comprises an improved construction or arrangement of the cutter carrying head which is specially intended to take all the lateral strains or stresses set up during the cutting or generating operation and eliminate overhang of the parts, the said head containing the whole of the mechanism for driving the cutting hob and enabling the 15 hob to be fed either directly into the worm wheel or like blank or tangentially to it.

The invention will be described with reference to the accompanying drawings, in which:—

25 Figure 1 is a front elevation of a worm wheel generating machine having the improvements applied thereto; Fig. 2 is a plan view of the machine; Fig. 3 is a side elevation of the machine, looking in the direction of the arrow A, Fig. 2, and Fig. 4 is a side elevation, partly in section, looking in the direction of the arrow B, Fig. 2.

According to our invention we employ a cutter head 1 slidable on ways on the machine frame 2 toward or away from the rotatable work table 3 carrying the spindle 4 on which the worm wheel or like blank to be cut is secured. The portion or face 5 of the head on which the slide 6 carrying the 35 hob spindle 7 is mounted, is made to incline, as is shown clearly in Figs. 3 and 4 from its lower edge outwardly or forwardly at a suitable angle to the vertical axis of the work spindle 4, the angle used being 40 approximately that of 45° though this may be varied somewhat either way without detriment. The guide surface of the frame is horizontal when the spindle 4 is vertical, and the guide face 5 of the head is arranged 45 at an acute angle to and subtending, or extending opposite to, the said guide surface of the frame. By this means the hob slide is rigidly supported at an angle to the vertical axis of the blank, and all thrusts due to 50 the cutting angles are correctly taken up, thus eliminating any detrimental effect on

the work which is so common on other worm wheel generating machines. At the same time overhang of the support for the hob spindle is eliminated, and we are enabled 55 to cut a very small wheel.

The machine is driven from a single pulley 8 by means of a friction clutch 9 operated by a hand lever 10 fast on the end of a rod 11 extending to the far side of the 60 machine. Motion is transmitted from the pulley 8 through a suitable change speed gear box 12 to a horizontal shaft 13 which, through suitable gears or dividing change wheels 14 gives motion to a shaft 15 from 65 which the work table 3 is driven by worm and worm wheel, not shown. The change speed gear 12 is controlled by a hand wheel 16 fast on the end of a rod 17 extending to the far side of the machine. The shaft 13 70 has a keyway 18 in which is slidable a key 19 carried by a bevel wheel 20 supported in a bearing in a bracket 21 carried by the head 1. The head 1 is slidable toward or away from the work table by means of a 75 feed screw 22 (Fig. 3) passing through a depending nut 23 on the head, the screw 22 carrying a bevel wheel 24 meshing with a bevel wheel 25 (Fig. 2) fast on a shaft 26 which extends to the same side of the 80 machine as the rods 11 and 17, and is provided with an operating hand wheel 27.

The head 1 carries all the mechanism for rotating and traversing the hob cutter, and the motion for driving such mechanism is 85 transmitted through the bevel 20 which slides to and fro on the main shaft 13 as the head is moved toward or away from the work table according to the diameter of the blank being cut. A short diagonal shaft 29 90 supported by the bracket 21 has fast on its lower end a bevel wheel 30 which meshes with the bevel wheel 20 and this shaft 29 drives both the hob rotating mechanism and the hob slide traversing mechanism. The 95 rotation of the hob is effected through a differential motion or compensating gear 28 at the upper end of the shaft 29 which differential motion drives a short diagonal shaft 31 having fast thereon a worm 32 100 meshing with a worm wheel 33 slidably keyed on the hob spindle 7. The short diagonal shaft 31 is an extension of the intermediate driving shaft 29, being arranged axially in line with it, and connected to it 105 by the compensating gear 28. This extension shaft 31 is connected positively with

the hob spindle 7. The directness of the drive from the shaft 13 to the hob spindle which will best be understood by an examination of Fig. 4, obviates the use of the long shafts 5 or driving connections between such parts, the importance and advantage of which will be readily appreciated by those skilled in the art of gear cutting.

The traversing of the hob slide 6 is effected as follows: Fast on the shaft 29 intermediate the bevel 30 and the differential motion 28 is a worm 34 which meshes with a worm wheel 35 fast on a transverse shaft 36. This transverse shaft drives, through a suitable change speed gear 37, a hollow transverse shaft 38, fast on which is a worm 39 meshing with a worm wheel 40 fast on a short shaft 41, which is supported in a suitable bearing 42, and has fast upon its front end a bevel wheel 43. A feed screw 44, passing through a nut 45 on the slide 6, carries a sliding clutch 46 rotatively connected to it, and two loosely rotatable bevels 47 and 48 meshing with the bevel 43. Movement of the clutch 46 into driving engagement with one or other of the bevels 47 or 48 which rotate in opposite directions, will cause the screw 44 to be rotated in one direction or the other whereby the slide 6 can be traversed in either direction according as the hob cutter employed be a right hand or a left hand cutter. Suitable automatic trip gear is provided to disengage the clutch at the end of movement of the slide in either direction. Any approved trip gear can be used, and the trip gear shown comprises lugs 60 on the slide 6, as shown in Fig. 1, adapted to come in contact with a collar 61 on a rod 62 which is slidable longitudinally in a bearing 63 on the head 1. The rod 62, as shown in Fig. 3, is operatively connected with a lever 64 secured on a rock-shaft 65 which is carried by the head. The lower end of the rock-shaft 65 has a lever 66 secured on it, and the free end of the lever 66 engages with a circumferential groove in the clutch 46, see Fig. 2, which clutch is splined on the feed screw 44 shown in Figs. 2 and 3. The rate of traverse of the slide 50 is determined by the change speed gear 37, which may be of any suitable construction to give the desired range of speeds, and is controlled by a hand wheel 49 located on the same side of the machine as the hand wheels 51 16 and 27 and hand lever 10. The hand wheel 49 is suitably graduated to show the feed per revolution of the hob.

To provide for variation of the speed of rotation of the hob relatively to the rate of feed of the slide 6 by which the hob is traversed the feed screw 44 is connected by change gearing 50 with a transverse shaft 51 passing through the hollow shaft 38 said shaft 51 having fast on its opposite end a worm 52 the angle of which is such that the

said worm will drive a worm wheel, but cannot be driven by a worm wheel. This worm 52 meshes with a worm wheel 53 integral with or secured to the casing of the differential motion 28 and by varying the speed of rotation of said casing the rotary speed of the hob is varied as will be understood. In the event of a left hand hob being employed a second intermediate wheel would be provided in the change gearing 50 in order to preserve the proper direction of rotation of the shaft 51. Disengagement of the clutch 46 at the end of movement of the slide 6 in either direction, that is to say on completion of a cut, stops the feed and also stops the differential action of the motion 28, as will be understood. When a cut has been completed, that is to say, when the trip motion has brought about disengagement of the clutch 46, the machine is stopped and the feed screw 44 is rotated by hand, by means of a handle applied to the squared end 54 of the screw, to reverse the movement of the slide 6 and carry the hob back to the commencing position. Through the change gears 50, shaft 51, worm 52 and worm wheel 53, the differential motion is simultaneously operated to cause the hob to be rotated as it is moved back, the remainder of the mechanism meanwhile remaining stationary. The speed of rotation of the hob as it is moved back is determined by the change gears 50. By the means described, the position of the hob relative to the work can be set up by hand, thereby relieving the operator of the considerable labor involved in rotating the work table to set up the hob to the work as is usual.

It will be observed that the whole of the hob operating mechanism is carried by the cutter head and moves therewith as the head is fed toward or away from the work table; the drive for rotating the hob is as direct as possible; differentiation for lead is on to the hob drive and not on to the work; the hob slide can be moved, and the hob rotated, by hand without affecting the remainder of the machine, while the control of the mechanism is so arranged as to be within easy reach of the operator when standing in the best position for viewing the cutting of the wheel.

The details of construction shown may be varied without departing from the invention within the scope of the appended claims.

Having thus described our invention, what we claim as new and desire to secure by Letters Patent is:—

1. In a milling machine, the combination, with a supporting frame, and a work spindle carried thereby; of a head carried by the frame and arranged adjacent to the work spindle and provided with a guide face arranged in an upwardly and forwardly inclined position with respect to the work

spindle, and a hob slide carried by the head and working against its inclined guide face.

2. In a milling machine, the combination, with a supporting frame provided with a guide surface, of a head slideable on the said guide surface and provided with a guide face arranged at an acute angle to and subtending the said guide surface, and a hob slide carried by the head and working against its inclined guide face.

3. In a milling machine, the combination, with a supporting frame, a head slideable on the frame, and a hob slide slideable in the said head; of a nut secured to the hob slide, a feed screw engaging with the nut and carried by the head, an intermediate driving shaft carried by the head, driving mechanism connecting the intermediate driving shaft with the feed screw, a main driving shaft carried by the said frame, and driving mechanism slideable longitudinally of the main driving shaft and operatively connecting it with the intermediate driving shaft.

4. In a milling machine, the combination, with a supporting frame, a head slideable on the frame, and a hob slide slideable in the said head; of an intermediate driving shaft carried by the head, a main driving shaft carried by the said frame, driving mechanism slideable longitudinally of the main driving shaft and operatively connecting it with the intermediate driving shaft, a hob spindle journaled in the hob slide, and intermediate driving mechanism operatively connecting the hob spindle with the said intermediate driving shaft.

5. In a milling machine, the combination, with a head, and a hob slide slideable in the head; of an intermediate driving shaft car-

ried by the head, an extension shaft arranged in line with the said shaft and also carried by the head, compensating gear operatively connecting the two shafts, a hob spindle journaled in the hob slide, driving devices operating to revolve the hob spindle from the said extension shaft, traverse mechanism, for the hob slide, operatively connected to and driven by the said intermediate driving shaft, and driving connections provided with change gearing and operatively connecting the said traverse mechanism with the said compensating gear and operating to vary the speed of rotation of the hob spindle relatively to the speed of traverse of the hob slide.

6. In a milling machine, the combination, with a head, a hob slide slideable in the head, and a hob spindle journaled in the hob slide; of a driving shaft formed in two sections, compensating gear operatively connecting the said sections, traversing mechanism, for sliding the hob slide, operatively connected to one shaft section, driving devices operating to revolve the hob spindle from the other shaft section, and driving connections provided with change gearing and operatively connecting the said traverse mechanism with the said compensating gear and operating to vary the speed of rotation of the hob spindle relatively to the speed of traverse of the hob slide.

In testimony whereof we affix our signatures in the presence of two witnesses.
